GEORGE H. FAICHNEY, OF WATERTOWN, NEW YORK, ASSIGNOR TO THE RANDALL-FAICHNEY COMPANY, OF BOSTON, MASSACHUSETTS, A CORPORATION OF MASSACHUSETTS.

MULTIPLE-ENGRAVING MACHINE.

1,359,241.

Specification of Letters Patent. Patented Nov. 16, 1920.

Application filed January 2, 1920. Serial No. 349,114.

To all whom it may concern:

Be it known that I, GEORGE H. FAICHNEY, a citizen of the United States, residing at Watertown, in the county of Jefferson and 5 State of New York, have invented certain new and useful Improvements in Multiple-Engraving Machines, of which the following is a specification.

This invention relates to improvements 10 in multiple engraving machines, particularly of the type employed for inscribing names, numbers and the like upon manufactured articles.

The object of the invention is to provide 15 a machine of the class, which may be controlled and actuated by any suitable pantographic mechanism, and which is arranged to engrave a plurality of articles in the same manner at the same time, by the employment of a single operator. A further 20 object is to provide a multiple engraver which is capable of simultaneously engraving articles of different size and shape, without requiring any special adjustment, or 25 alteration or change of any of the parts of the machine, and wherein the graving or scribing may be effected on flat, concave or convex surfaces, by means of self-adjusting 30 engraving tools, which are arranged to simultaneously gravitate to the engraving position, and to be automatically released at the end of the engraving operations. A further object is to provide an upright frame 35 for supporting the engraving tools and related parts in vertical tiers, the said frame adapted for universal movements in a horizontal plane by a simple connection with the pantograph mechanism. And a further object is to provide a plurality of 40 work-supporting members upon which adjustable work holders are slidably mounted, the said members being disposed horizontally one above the other and each member arranged to adjustably support a number 45 of articles to be engraved.

I attain these objects by the means set forth in the detailed description which follows, and as illustrated by the accompanying drawings, in which—

50 Figure 1 is a front side elevation of the complete machine. Fig. 2 is an end elevation of the same. Fig. 3 is a view; showing a modified construction of certain parts of the stationary frame. Fig. 4 is a top-

plan view of the machine. Fig. 5 is an enlarged broken top face view of one of the work supporting members; showing a pair of the adjustable work holders. Fig. 6 is a cross-section, taken on line 6—6 of Fig. 5. Fig. 7 is a view of one of the clinical thermometers; showing the numbers engraved thereon by the machine. Fig. 8 is a view of the barrel of a common hypodermic syringe, which may be engraved at the same time the smaller caliber thermometers are engraved, 65 where the matter is common to both articles. And Fig. 9 is an enlarged side elevation of one of the engraving tools and its supports.

The present machine comprises two upright frames, one stationary, the other movable, and the stationary frame preferably being disposed within the movable frame.

In the drawings, 2 represents a base, which supports the entire engraving mechanism, and upon which is rigidly mounted the stationary frame, which consists of the following parts: 3 designates a plurality of posts, which mark the four corners of the frame, upon which are rigidly mounted horizontal and transverse rails 3', the front ends of said rails being tied together by a brace 3^a. Upon each rail 3' is mounted a plurality of similar spaced posts 3^b, which alternate with similar transverse rails 3^c, the latter being disposed in different horizontal planes, for supporting a number of horizontal and longitudinal work-supporting bars 4, the latter preferably being positioned one directly above the other, as shown in Figs. 1 and 2. The bars 4 are removable 90 for loading and unloading the articles to be engraved, and preferably consist of iron or steel, which retain their positions in the frame by their own weight. The top face of each bar 4 is provided with a longitudinal dove-tail groove 4', in which is slidable a plurality of adjustable work holders 4^a, the latter comprising brackets whose bases conform to and are slidable in the groove 4'. Each bracket is provided with an upright lug 4^c, which is perforated to receive and hold the work C. These lugs are also provided with threaded perforations to receive threaded connecting and adjusting rods 4^d, by which the said brackets may be moved toward and away from each other and made to tightly grip and hold the work C. The screws 4^d are of sufficient length to permit

the handling of work of different lengths, as shown by the full and dotted lines in Figs. 1 and 5. The brackets or holders 4^a preferably snugly fit in the grooves 4', so that no additional securing means, other than friction, is needed for holding them in the various adjusted positions.

The engraving is accomplished by a plurality of similar gravitational needles or tools 5, which are preferably arranged in horizontal rows, one above the other, the same as the bars 4. These needles are supported and given their proper movements for effecting the engraving by the movable frame, which will now be described: 9—9' designate similar elongated grooved members comprising two transversely arranged ball-bearings, the members 9 being rigidly secured to the base 2, while the members 9' are allowed longitudinal movements relatively to the members 9 by means of balls 9^a, which play in the facing grooves of said members. 10—10' designate similar grooved members of another pair of bearings, which extend longitudinally through the machine, at right angles to the bearings 9—9', in which the members 10 are mounted on the tops of the members 9', and are rigidly secured thereto by braces 10^a, the latter only shown in Fig. 2. Balls 10^b are disposed in the facing grooves of the members 10—10', and these balls support the members 10', and allow them longitudinal movements independently of the other members. The top-most members 10' are tied together at their opposite ends by transverse cleats 10^c, which constitute the normal base of the movable frame. Upon the cleats 10^c are correspondingly mounted columns 11—11' of equal height, which at intervals in their height connect to and support the opposite ends of longitudinal bars 7, the said bars being positioned slightly above and at right angles to the rails 3^e of the stationary frame.

The engraving needles or tools 5 are preferably detachably mounted in the lower ends of cylindrical plungers 6, the latter being reciprocably and rotatably mounted in the vertical arms of L-shaped brackets 6', which are adjustably secured to the bars 7 by bolts 6^a, the latter passing through slots 6^b in the horizontal arms of said brackets and are threaded into the bars 7. By this means the needles 5 are properly positioned relatively to the work C carried by the holders 4^a. The plungers 6 are provided with fingers or arms 6^c, which extend at right angles to their top ends. These fingers normally rest upon the top edges of similar rocking-bars 12, which are disposed horizontally above and parallel to the bars 4 and 7. The rocking-bars 12 are journaled in bearing blocks 12' and 12'' which are supported respectively by the columns 11—11' and the bars 7. The corresponding ends of the rock-

ing-bars 12 are fitted with similar wheels 12^a, which are tied together for simultaneous operation by a rod 12^b, the latter being operatively connected with a pedal 12^c by a cord 12^d, a lever 12^e, and a link 12^f (see Fig. 1). The rocking-bars 12 control the vertical movements of the tools 5 and plungers 6, and when the said parts are in the full line position shown in Figs. 4 and 9, the bars 12 sustain the full weight of the plungers and needles, which are then in their upper or released positions. The bars 12 are moved to and maintained in the last named position by a spring 13, one end of which is attached to the adjacent column 11, while its opposite end is connected to an arm 13' fixed to one of the wheels 12^a (see Figs. 1 and 4). The spring 13 exerts its tension for moving the bars 12 in the opposite direction to that of the pedal 12^c.

The movable frame, which supports the engraving needles 5, is actuated during the engraving operations by a pantographic mechanism, which is controlled by the operator while he traces the copy A, which is reproduced by the needles on the work C. The pantograph mechanism consists of a substantially horizontal tracer arm 14, which supports at one end a tracing pencil or point 14'. The arm 14 extends rearwardly and passes beneath the stationary and movable frames, and its rear end is pivoted to an oscillating upright lever 15, whose upper end is pivoted by a bolt 15' in a horizontally disposed frame 16. The frame 16 is mounted beneath a stationary arch 17, which is rigid on the base 2, and the said frame is pivoted at 16^a, for certain rocking movements, to a bolt 17', which depends from the center of the arch. The pivots 16^a allow the frame 16 and the lever 15 to rock or oscillate like a pendulum, as indicated by the dotted lines in Fig. 1. The upright lever 15 alone is operatively connected to the movable frame by a rod 18, one end 18' of which is a yoke, which is connected to the lever 15 below the pivot 15', by pivots 18^a. The opposite or outer end of the rod 18 is journaled in a bearing 19 which is adjustably supported by an inverted V-shaped brace 20, the latter being rigidly secured to the rear ends of the cleats 10^c, and is therefore a part of the movable frame. The fork 18' is adjustable vertically on the lever 15 for varying the movements of the movable frame by a bolt 18^c and a thumb-nut 18^d. When the operator moves the tracer arm 14 forward and backward over the copy A the lever 15 moves correspondingly, and causes the rod 18 to move the needle-supporting frame in the same directions, as indicated by the dotted lines in Figs. 2 and 4, and during the said operation, the whole movable frame down to and including the bearing members 9' participate in the said

forward and backward movements. When the lever 14 is swung toward the right and the left (see Figs. 1 and 4), the movable frame including only the topmost members 5 10' of the bearings move longitudinally on the balls 10^a, as indicated by the dotted lines in Figs. 1 and 4. By these means the frame which actuates the engravers 5 is given substantially universal movements in a horizontal plane on the several ball bearings 9 and 10. These bearings exert so little friction, that the movable frame readily responds to the tracer arm 14, and requires very little force or power to operate it. The movable 15 parts of the machine are held in place upon the relatively long bearings 9 and 10 alone by gravity.

The present machine is designed and constructed particularly for engraving the degree numbers on the thermometers C, and in order to properly carry out this work, it is essential that the thermometers which are of relatively small caliber and transparent, be placed between the operator and the light, 20 so that the operator may accurately note the position of the relatively fine graduations on the tubes C, and adjust the work C so that the numbers may be engraved directly opposite the degree marks to which they refer. 25 For these reasons, it is preferable to dispose the work, as well as the engraving needles in vertical tiers, as shown, so that none of the mechanism intervenes between the work and the light, to interfere with the precise adjustment of the work C, and the close inspection of the work during the engraving operations.

In Fig. 3 I have shown a modification consisting principally of substituting angular 40 braces 21 for the front posts 3^b, for permitting the ready and convenient handling of the work-supporting bars 4. The bars 4 in Fig. 3 are provided with depending studs 4^e, which are received in corresponding sockets formed in the rails 3^c, for holding the bars from accidentally shifting during the engraving operations.

In Fig. 7 is shown one of the thermometers which is graduated in the usual manner 50 and then engraved with the degree numbers by the present machine. Fig. 8 illustrates the barrel C' of the usual hypodermic syringe, the same being of larger caliber than the thermometer, and which may be inserted 55 in the machine and engraved with suitable matter common to both kinds of work, without requiring any adjustment of the parts. When the barrels C' are placed in the machine, a centering part 22 is usually inserted 60 in the mouth of the barrel, and its free end then inserted in the regular perforation in the lug of the holder, which takes one end of the thermometers. In case some of the thermometers are of larger diameter than 65 the others, the needles 5 merely gravitate a

less distance in order to come into engraving contact with the work.

Obviously some changes or modifications may be made in the parts of the machine, and that the number of the work-supporting 70 bars 4, as well as of the needles 5 and related parts may be increased or diminished, as compared with what is shown herein, without departing from the spirit of the invention. 75

Having thus described my invention, what I claim, is—

1. In a multiple engraving machine, an upright stationary frame, a plurality of work supporting bars mounted on said frame at different levels, an upright movable frame partially inclosing the other frame, a plurality of ball-bearings supporting said movable frame and adapted for guiding said frame in different directions in a horizontal plane, and a plurality of engraving needles carried by said movable frame, said needles arranged in rows one row above the other, and adapted to simultaneously engrave work carried by said bars 90 at the different levels when actuated by said movable frame.

2. In a multiple engraving machine, a stationary frame, a plurality of work supporting bars mounted in said frame at different levels, a movable frame partially inclosing the other frame, a plurality of ball bearings supporting said movable frame and adapted for guiding said frame in different directions in a horizontal plane, a plurality of 100 gravitational engraving needles carried by said movable frame, said needles arranged in parallel rows, one row above the other, adapted to engrave work carried by said bars when actuated by said movable frame. 105

3. A multiple engraving machine, including a stationary frame, a plurality of work-supporting bars carried by said frame at different levels, a movable frame, a plurality of ball-bearings supporting the movable 110 frame and adapted to guide said frame in different directions in a horizontal plane, a plurality of gravitational engraving needles carried by the movable frame, said needles arranged in rows disposed in a vertical tier 115 and paralleling said bars and adapted to simultaneously engrave work carried by said bars when actuated by said movable frame, and means for operating said movable frame.

4. A multiple engraving machine including a plurality of gravitational engraving needles adapted to effect engraving by their own weight, said needles arranged in rows and disposed one row above the other, a plurality of rockable supports for said needles 120 adapted to normally hold said needles out of engagement with the work, means for moving said needles simultaneously toward the work, and means for moving the several rows of needles in the corresponding hori- 125 13

zontal planes for simultaneously effecting the engraving of work disposed at different levels.

5. A multiple engraving machine, including an upright stationary frame, a plurality of work-supporting bars mounted in said frame at different levels, an upright movable frame, a plurality of ball-bearings supporting the movable frame and adapted for 10 guiding said frame in different directions in a horizontal plane, a plurality of engraving needles supported by the movable frame, said needles arranged in rows, one row above the other and adapted to simultaneously 15 engrave work carried by said bars at the different levels when actuated by said movable frame, means for causing said needles to simultaneously gravitate into engraving contact with the work, and means 20 for moving and holding said needles out of engagement with the work.

6. A multiple engraving machine including an upright stationary frame, a plurality of work-supporting bars disposed one above 25 the other in said frame, means for adjusting each piece of work on said bars, a plurality of engraving tools disposed in rows above the corresponding bars, a movable frame for supporting and actuating said tools, said frame movable horizontally, means for moving the tools of the several 30 rows toward the work in the same time, and means for simultaneously lifting all of said tools away from the work at the end 35 of each engraving operation.

7. In a multiple engraving machine, a plurality of gravitational engraving tools adapted to perform identical work simultaneously, said tools arranged in horizontal 40 rows, one row above the other, bars for supporting work to be engraved beneath the corresponding rows of tools, said bars arranged to hold the work between the operator and the light for permitting close inspection 45 of the work during the engraving operations, a frame adapted for universal movements in a horizontal plane for supporting and actuating said tools, means for effecting the simultaneous gravitation of all 50 of said tools toward the work, and means for automatically moving all of the tools away from the work.

8. A multiple engraving machine, including a plurality of gravitational engraving 55 tools adapted to perform identical work, said tools arranged in horizontal rows and the rows arranged in a vertical tier, a bar for supporting work to be engraved beneath each row of tools, rocking bars disposed above the corresponding rows of tools 60 adapted for holding said tools away from the work, means for rocking said bars for permitting the simultaneous gravitation of

all of said tools toward the work, means for adjusting the work relatively to each of 65 said tools, and means for moving said tools in different directions horizontally for effecting the engraving of the work.

9. In a multiple engraving machine, a plurality of engraving tools adapted to 70 effect engraving by their own weight, said tools arranged in horizontal rows, one row above the other, horizontal bars for supporting the work beneath the rows of tools, 75 means for adjusting the work on said bars, a frame for supporting and actuating said tools, said frame movable only in a horizontal plane, means for operating said frame, means for holding said tools away from the work, and means for lowering 80 said tools into engraving contact with the work.

10. In a multiple engraving machine, a plurality of engraving tools adapted to perform identical work simultaneously and to 85 be held in engraving contact with the work by gravity, said tools arranged in horizontal rows, one row being disposed above the other, means for simultaneously withdrawing all of said tools from the work, a stationary work support disposed beneath each 90 row of tools, work holders adjustable on said supports, a frame for supporting and actuating said tools, said frame movable in a horizontal plane, means for guiding said frame in different directions horizontally for causing said tools to engrave various 95 characters on the work, and means for actuating said frame.

11. In a multiple engraving machine, the 100 combination with a pantograph mechanism, of a movable frame, means for operatively connecting said mechanism with said frame for imparting to said frame various movements in a horizontal plane, a plurality of 105 work supporting bars arranged one above the other, a stationary frame for supporting said bars, a plurality of gravitational engraving needles supported by and movable with said movable frame, said tools arranged in horizontal rows disposed at different levels parallel to said bars, rocking bars controlling the vertical movements of said needles, said rocking bars disposed at different levels corresponding to the several 110 rows of needles, means for operating said rocking bars for moving the needles away from the work, means for operating said rocking bars for allowing all of the needles to gravitate toward the work in equal time, 115 and means for adjusting the work on said supporting bars so that the light may aid the operator to inspect the work during the engraving operations.

In testimony whereof I affix my signature. 125
GEORGE H. FAICHNEY.
